UNITED STATES PATENT OFFICE.

LEWIS A. MAPEL, OF ST. LOUIS, MISSOURI, ASSIGNOR TO MECHANICAL DEVELOPMENT COMPANY, OF ST. LOUIS, MISSOURI, A CORPORATION OF MISSOURI.

DESIGN FOR A GAGE-CASING.

51,285.

Specification for Design.

Patented Sept. 18, 1917.

Application filed January 29, 1917. Serial No. 145,337. Term of patent 14 years.

To all whom it may concern:

Be it known that I, LEWIS A. MAPEL, a citizen of the United States, residing at St. Louis, Missouri, have invented a certain new, original, and ornamental Design for a Gage-Casing, of which the following is a specification, reference being had to the accompanying drawing, forming part thereof.

Figure 1 of the drawings is a front elevational view of my new design for a gage casing; and

Fig. 2 is a top plan view thereof.

I claim:

The design for a gage casing, as shown.

LEWIS A. MAPEL.
